UNITED STATES PATENT OFFICE

165,767

BACK GUARD FOR A RANGE

Ralph E. Kruck, Clinton, Conn., assignor to Florence Stove Company, Gardner, Mass., a corporation of Massachusetts

Application May 5, 1950, Serial No. 9,746

Term of patent 14 years

(Cl. D81—25)

To all whom it may concern:

Be it known that I, Ralph E. Kruck, a citizen of the United States and residing at Clinton, in the county of Middlesex, State of Connecticut, have invented a new, original, and ornamental Design for a Back Guard for a Range, of which the following is the specification, reference being made to the accompanying drawing, forming a part thereof.

Fig. 1 is a top plan view of a back guard for a range, showing my new design.

Fig. 2 is a front elevation of the back guard.

Fig. 3 is an end elevation looking from the right of Fig. 1.

Fig. 4 is a fragmentary sectional elevation taken on the line 4—4 of Fig. 2.

I claim:

The ornamental design for a back guard for a range, as shown.

RALPH E. KRUCK.
